(57) **CLAIM**

We claim the ornamental design for a bottle holder, as shown and described.

DESCRIPTION

FIG. 1 is a perspective view of one embodiment of the bottle holder of our design with a bottle shown in broken line; FIG. 2 is a left side view of the bottle holder of FIG. 1; FIG. 3 is a right side view of the bottle holder of FIG. 1; FIG. 4 is a front view of the bottle holder of FIG. 1 in a use position;

FIG. 5 is a rear view of the bottle holder of FIG. 1 in a use position;

FIG. 6 is a front view of the bottle holder of FIG. 1 tilted to better illustrate the details thereof;

FIG. 7 is a rear view of the bottle holder of FIG. 1 tilted to better illustrate the details thereof;

FIG. 8 is a perspective view of another embodiment of the bottle holder of our design with a bottle shown in broken lines;

FIG. 9 is a left side view of the bottle holder of FIG. 8;

FIG. 10 is a right side view of the bottle holder of FIG. 8;

FIG. 11 is a front view of the bottle holder of FIG. 8 in a use position;

FIG. 12 is a rear view of the bottle holder of FIG. 8 in a use position;

FIG. 13 is a front view of the bottle holder of FIG. 8 tilted to better illustrate the details thereof; and,

FIG. 14 is a rear view of the bottle holder of FIG. 8 tilted to better illustrate the details thereof.
